UNITED STATES PATENT OFFICE.

MARC BIRKIGT, OF BOIS-COLOMBES, FRANCE.

CYLINDER ENGINE.

Application filed June 20, 1927, Serial No. 200,815, and in Belgium August 12, 1926.

This invention relates to engines provided with cylinders having jackets for fluid circulation and more particularly, although not exclusively, to internal combustion engines, 5 since it is in their case that the invention would appear to be of the greatest value.

It has for its principal object, to so construct such engines, that the jackets shall be of simpler construction and more easily 10 mounted than has hitherto been the case, and that, where a portion of the fluid contained in the jacket is in direct contact with the cylinder, more efficient fluid-tight joints may be formed at the points of connection 15 of the jacket to the cylinder.

The jacket provided for the cylinder or cylinders of the engine includes in a known manner, parts capping the cylinder or cylinders and enveloping it or them laterally 20 at least in part so that the fluid contained in the jacket will be in direct contact with the lateral wall or walls of the said cylinder or cylinders.

According to the invention the jacket is 25 so formed that it comprises a portion which forms the upper end of the cylinder and is connected to or extends into the jacket proper, and screw threaded so that the upper end of the cylinder, which is correspondingly threaded, may be screwed thereinto. The lower extremity or edge of said portion co-operates with a collar on the said cylinder, and appropriate packing means is interposed between the collar and the said 35 lower edge of said portion. The lower extremity of the portion of the jacket enveloping the cylinders is closed by a wall, in which circular openings are formed to receive the said cylinders, and appropriate 40 packing means are provided for insuring fluid-tight joints between said openings and the cylinders.

In order that the invention may be clearly understood, it will now be described 45 with reference to the accompanying drawing, but it is to be observed that the description and drawings are given merely by way of example.

Fig. 1 is a diagrammatic vertical axial 50 section of the cylinder of an internal combustion engine provided with a jacket for water constructed according to the invention, the section being taken on the line 1-1, Fig. 2 and looking in the direction of the 55 arrow in that figure.

Fig. 2 is a section on the line 2-2, Fig. 1. The engine itself, with the exception of the water jacket and the cylinder, is constructed in the ordinary manner.

The water jacket is formed, as is customary, of a heat-conducting metal which is strong and light, for instance aluminium or an alloy of aluminium, or from any other metal having like properties.

The jacket comprises a part *a* mounted on the upper end of the cylinder *b*. This part *a* comprises a sort of inverted basin, the side wall of which is traversed by openings *c* to receive spark plugs. The bottom of the basin is provided with seats for the 70 intake and exhaust valves, only one of which *d* is shown.

The portion *a* is formed with conduits *e* communicating with said seats and with bosses which are perforated to serve as 75 guides for the valve rods.

Depending from the part *a* is a part *f* which envelops at least parts of the walls of the cylinder, so that, when the joints between the part *f* and the wall of the cylinder are 80 made tight, the water contained in the space between the part *f* and the exterior of the cylinder wall is in direct contact with the wall of the cylinder.

The interior of the side wall of the inverted basin-like part of the part *a* of the jacket below the opening *c* is, for an appropriate distance, cylindrical and of a diameter equal to the outer diameter of the cylinder. It is internally screw threaded at 85 *g* and terminates at its lower end in a flat horizontal edge *h*. The part *f* of the jacket is so constructed that, once the cylinder is in position, tight joints are formed in any appropriate manner between its upper and lower ends and the upper and lower ends, respectively, of the cylinder in the manner about to be described.

The cylinder *b* consists of a tube open at both ends, and having its upper end externally screw threaded so that it is adapted to screw into the screw threaded portion *g* of the part *a*. It also has, adjacent its upper end, a collar *i* which is adapted, when the cylinder is screwed home into the screw threaded portion of the part *a*, to bear against the flattened edge *h* of the portion *a*; and packing *j* is interposed between the flange or collar *i* and said edge *h* so that a tight joint between the cylinder and the 100

jacket at this end is ensured. As will be seen the member *a* forms the upper end of the cylinder.

In the preceding description it is assumed 5 that the engine is a single cylinder engine.

If the engine comprises a plurality of cylinders, the jacket is of the type shown in Fig. 2, the parts *a* associated with the different cylinders being connected on the one 10 hand to the wall of the water jacket *k* by means of masses *l* which are traversed by the openings *c* for the spark plugs. The water jacket wall *k* is closed at the lower extremity of the jacket by means of a base *m* 15 in which are provided circular openings to permit of the passage of the different cylinders therethrough.

In order to ensure a tight joint between each cylinder *b* and the lower extremity of 20 its associated jacket portion *f*, the following means are preferably provided.

The cylinder is provided, adjacent its lower end, with a cylindrical collar *n* of 25 greater diameter than the collar *i* and also of greater diameter than that of any of the strengthening ribs *o* which may be formed on the exterior of the cylinder. The lower end of the jacket *f* is provided with a bore through which the said collar *n* passes, thus 30 forming an annular space between the lower surface of collar *n*, the inner cylindrical surface of the lower extremity of jacket *f*, and the outer wall of cylinder *i*. Packing *p* is rammed into the annular space between 35 jacket *f* and cylinder *i*, below the collar *n* and is compressed therein by a pressure ring *g* which is screw threaded on its inner perimeter to engage screw threads on the wall of the cylinder. The advantages of this form 40 of assembly are, (1) the jacket walls *f* may be made thin, thus diminishing the weight of the motor casting; (2) as a result of the thinness of jacket wall *f*, the distance between adjacent cylinders is diminished with 45 consequent diminution of the length of the crank shaft and the weight and length of the motor. The pressure ring *g* may be ribbed and preferably is split to permit its diameter

to be reduced and to facilitate its insertion within the lower end of the jacket wall *f*. 50 By this means both a satisfactory tight joint is formed and provision is made for sliding movement between the end of the jacket and the collar so that differences between the expansions of the jacket, which may be of 55 aluminium, and of the cylinder, which may be of steel of high resistance, are compensated for.

The weight of the motor block may be carried by a flange formed on the lower extremity of jacket *f*. The cylinder *i* is, therefore, free to expand and contract without working against weight or end pressure of any kind. 60

It is to be understood that the invention 65 is not limited in any way to that method of application or to those constructional embodiments of its various parts which have been more particularly indicated above. All modifications are included, falling within 70 a fair interpretation of the claim.

What I claim and desire to secure by Letters Patent of the United States of America is:—

A motor assembly comprising in combination, a hollow jacket, said jacket being formed with an internal cylindrical sealing surface, an open-ended cylinder removably connected at one of its extremities to said jacket adjacent the head thereof, said cylinder having its free extremity projecting beyond the sealing surface and having an annular external projection formed thereon intermediate its extremities, said annular projection having a diameter corresponding to that of the cylindrical sealing surface of the jacket and a length less than that of the sealing surface of said jacket, means for packing the free space between the cylinder and the cylindrical sealing surface of the jacket, and means insertable from the crank shaft end of the cylinder for maintaining said last-named means in position. 75 80 85 90

In witness whereof I affix my signature.

MARC BIRKIGT.
